UNITED STATES PATENT OFFICE.

JOHN JOSEPH SLEPICKA, OF CHICAGO, ILLINOIS.

COMBINED LOCK AND ALARM.

1,122,809.

Specification of Letters Patent.

Patented Dec. 29, 1914.

Application filed October 2, 1913. Serial No. 793,047.

To all whom it may concern:

Be it known that I, JOHN J. SLEPICKA, a citizen of the United States, residing at Chicago, in the county of Cook and State of Illinois, have invented a new and useful Combined Lock and Alarm, of which the following is a specification.

This invention relates to a combined lock and alarm and is more particularly an improvement upon the structure disclosed in Patent No. 990,915, issued to me on May 2, 1911.

In my patented structure herein referred to, the steering wheel is mounted upon a shaft or pillar adapted to be swung upwardly out of active position, means being provided whereby the said pillar can be locked in elevated position. A combination lock is utilized and an alarm is provided whereby tampering with the lock by unauthorized persons will result in the sounding of the alarm.

One of the objects of the present invention is to provide an improvement in the combination or permutation lock to be used in connection with the steering post whereby the structure is greatly simplified and can be more accurately brought to the graduations of the predetermined combination than heretofore.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a section through the hinge used in connection with the steering post and showing the lock and the parts constituting the present invention, the alarm circuit being shown diagrammatically. Fig. 2 is a plan view of the base of the pillar and the parts carried thereby. Fig. 3 is a vertical section through the base and the lower portion of the pillar and showing the locking sleeve in section.

Referring to the figures by characters of reference 1 designates the lower section of the steering shaft or pillar to the upper end

of which is secured a cap or plate 2 having a notched flange for engagement by locking means, said flange being shown at 3.

A cylindrical ear 4 is formed along the upper edge of the plate 2 and has a rectangular opening 5 therein.

A rectangular sleeve 6 is slidably mounted within this opening 5 and has a cylindrical bore 7 into which opens a longitudinal slot 8 formed along the center of one face of the sleeve.

A combined actuating and pivot pin or bolt 9 extends through the bore 7 and beyond the ends of sleeve 6, the said bolt constituting bearings for ears 10 and 11 formed along one edge of the upper plate or foot 12. A latch member 15 is carried by this foot for engaging the notched flange 3 and the upper section 16 of the steering pillar or shaft 75 extends from the foot 12.

Each of the ears 10 and 11 has a rectangular socket 19 in its inner end which is normally out of register with the opening 5 and sleeve 6 as clearly indicated by dotted lines in Fig. 3. When, however, the plate 12 and section 16 are swung outwardly these sockets will be moved into register with the opening 5 so as to permit the sleeve 6 to be shifted longitudinally into either of the 35 sockets and thus lock the plate 12 in raised position relatively to the plate 2. The upward movement of plate 12 and section 16 can be stopped as soon as the sockets are brought into register with openings 5, by 90 providing stop screws 20. These screws are arranged in the side wings 12¹ of plate 12 with their heads upon the inner sides of the wings. Grooves 2¹ are formed in the sides of the plate 2 and when the plate 12 is 95 swung upwardly the heads of screws 20 enter the grooves and come against the end walls of the grooves. The ears 10 and 11 are both provided with sockets 21 and 22, respectively, in their outer ends, the socket 21 being closed by means of a screw cap 23 while another screw cap 24 having a central opening 25 constitutes the closure for the socket 22.

Lugs 26 and 27 extend radially from the pivot pin or bolt 9 and are spaced apart a distance slightly greater than the length of sleeve 6. It will be apparent, therefore, that the bolt 9 is capable of a sliding movement in the direction of its length before one of 110 the lugs is brought into contact with the sleeve. One end of the bolt 9 is reduced and

threaded, as at 9¹, and is engaged by a stem 28¹ which projects through the opening 25 in cap 24 and terminates in a disk 28 formed with an annular channel 29 upon the inner portion of the periphery thereof.

A sleeve 30 is mounted for rotation in the opening 25 and upon the sleeve 28¹ and the outer end of this sleeve is formed with a collar 31 adapted to fit snugly against the 10 inner face of disk 28. An annular flange 32 is formed on the collar and fits snugly within the annular channel 29. This flange 32 may be provided on its outer face with graduations such as indicated at 33 and additional graduations such as indicated at 34 can be formed on the exposed portion of the periphery of disk 28.

The inner end of sleeve 30 is formed with an annular flange 35 having a peripheral 20 notch 35¹. A disk 36 is secured to and rotates with bolt 9 close to the reduced portion 9¹ and arranged on one face of this disk is a flange 37 which extends around and lies flush with flange 35. This disk 36 and flange 25 37 has a notch 39 adapted to move into or out of register with notch 35¹. A plug 38 of insulating material is extended into the socket 22 and is slightly narrower than the notches 35¹ and 39. Thus when sleeve 30 is 30 rotated to a predetermined position the notches 35¹ and 39 will register and can be slipped over the plug 38. A contact 40 is formed upon plug 38 and is connected to one wire of a circuit including an alarm 41 35 and a source 41¹ of electricity. The other wire of the circuit is grounded to the machine.

In order that the bolt 9 can be rotated readily, a knob 42 is extended from the outer 40 face of disk 28 and in order that the amount of movement of the bolt inwardly or outwardly relative to the closure 24 can be accurately determined, a graduated strip 43 is secured to the wheel 11 and is extended outwardly along lines parallel with the path of movement of the bolt 9 and disk 28.

Under normal conditions the parts are positioned as indicated in the drawings. When the upper section 16 of the steering post is 50 swung upwardly to the limit of its movement the sockets 19 are brought into register with the opening 5. Bolt 9 can then be shifted longitudinally by properly manipulating the disk 28 and sleeve 30, so as thus 55 to bring sleeve 6 into one of the sockets 19, thereby locking the section 16 against return movement relative to section 1. In order to shift the bolt 9 into locking position, it is necessary to rotate sleeve 30 relative to the 60 disk 28 until predetermined graduations 33 and 34 are brought into register. This brings notch 35¹ which is formed in flange 35 into register with the notch 39 formed in the disk 36. With notch 35¹ and notch 39 65 thus registering, the disk 28 and sleeve 30

are rotated together until a predetermined graduation is brought into line with the indicating edge of the blade or strip 43. Thus it can be determined when the notches 35¹ and 39 are in alignment with the plug 38. 70 The next adjustment is the inward shifting of the disk 28 and sleeve 30 until the inner face of flange 32 is brought opposite a predetermined graduation on the strip or plate 43. During this movement of the parts the 75 flange 35 and disk 36 will be brought into inner position back of the plug 38 and the bolt 39 will be shifted so as to cause sleeve 6 to be seated within one of the notches 19. By stopping when a predetermined graduation of strip 43 is reached, the flange 35 can 80 rotate back of plug 38 without coming into contact with the contact 40. If, however, the parts should not be moved inwardly a sufficient distance, they will when rotated, 85 come against the contact and thus complete a circuit to the alarm 41.

What is claimed is:—

1. The combination with a slidable and revoluble locking member, of a disk revoluble with said member and having a peripheral flange extending from one face thereof, there being a notch in the periphery of the disk and intersecting the flange, a stem engaging the locking member and bearing against and revoluble with the disk, a knob at the outer end of the stem and having a graduated periphery, a sleeve revoluble on the stem and having a flange bearing against the disk and provided with a notch movable into register with the notch in the disk, a graduated flange on the sleeve and extending around and upon the knob, an insulation plug adapted to limit the sliding movement of the locking member until 90 said notches in the disk and flange are brought into register and into alignment with the plug, a contact upon one face of the plug, and an alarm electrically connected to a source of energy and to the sleeve and 95 contact.

2. The combination with a slidable and revoluble locking member, of a disk revoluble with said member and having a peripheral flange extending from one face 100 thereof, there being a notch in the periphery of the disk and intersecting the flange, a stem engaging the locking member and bearing against and revoluble with the disk, a knob at the outer end of the stem and having a graduated periphery, a sleeve revoluble on the stem and having a flange bearing against the disk and provided with a notch movable into register with the notch 105 in the disk, a graduated flange on the sleeve and extending around and upon the knob, an insulation plug adapted to limit the sliding movement of the locking member until 110 said notches in the disk and flange are brought into register and into alignment with the plug, a contact upon one face of the plug, and an alarm electrically connected to a source of energy and to the sleeve and 115 contact.

with the plug, a contact upon one face of the plug, fixed means coöperating with the graduated flange for indicating the extent of sliding movement of the locking member, 5 and an alarm electrically connected to a source of energy and to the sleeve and contact.

3. The combination with a slidable and revoluble locking member having a reduced 10 threaded end, of a disk fitted on said member close to the reduced end and revoluble with the member, said disk having a peripheral flange extending from one face thereof, there being a notch in the periphery of the disk and intersecting the flange, 15 a stem engaging the reduced end of the locking member and bearing against and revoluble with said disk, a knob at the outer end of the stem and having a graduated periphery, a sleeve revoluble on the stem and 20

having a flange bearing against the disk and provided with a notch movable into register with the notch in the disk, a graduated flange on the sleeve and extending around and upon the knob, an insulation 25 plug adapted to limit the sliding movement of the locking member until said notches in the disk and flange are brought into register and into alinement with the plug, a contact upon one face of the plug, and an alarm 30 electrically connected to a source of energy and to the sleeve and contact.

In testimony that I claim the foregoing as my own, I have hereto affixed my signature in the presence of two witnesses.

JOHN JOSEPH SLEPICKA.
